UNITED STATES PATENT OFFICE.

JOHN N. ANKROM, OF SISTERSVILLE, WEST VIRGINIA.

PULLEY AND ROPE GUIDE.

1,242,636.

Specification of Letters Patent.

Patented Oct. 9, 1917.

Application filed May 5, 1916. Serial No. 95,539.

To all whom it may concern.

Be it known that I, JOHN N. ANKROM, a citizen of the United States, residing at Sistersville, in the county of Tyler, State of West Virginia, have invented a new and useful Pulley and Rope Guide; and I do hereby declare the following to be a full, clear, and exact description of the invention, such as will enable others skilled in the art to which it appertains to make and use the same.

The present invention relates to a pulley and rope guide, and has for its object to provide a device of this character which embodies novel features of construction where by the rope guides are securely held in proper position when the pulley is in operation, although they can be readily removed from the pulley when such is desired.

Further objects of the invention are to provide a pulley and rope guide which is comparatively simple and inexpensive in its construction, which will successfully withstand heavy strain without breakage, which will effectively remove all kinks from the rope or cable as it passes around the sheave, and which admits of the rope guides being readily placed in position or removed therefrom without the use of any special tool.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a pulley constructed in accordance with the invention, the guide members being shown in operative position by full lines, and by dotted lines as swung into the position assumed preparatory to disengaging the right hand guide member from the pulley frame.

Fig. 2 is an edge view of the pulley.

Fig. 3 is a detached perspective view of one of the guide members, portions being broken away.

Fig. 4 is a fragmentary sectional view through the top of the pulley frame.

Fig. 5 is a fragmentary vertical sectional view through the lower portion of the pulley.

Corresponding and like parts are referred to in the following description and indicated

in all the views of the drawing by the same reference characters.

The pulley frame may be conveniently formed from a single piece of sheet material which is of a proper thickness to withstand the strains to which it will be subjected when in use. This frame includes a pair of opposed side plates 1 which are similar in size and shape, being connected at the upper ends thereof by the top pieces 2. A suspending ring 3 has a swiveled connection with the top piece 2. In the present instance this ring is shown as formed from a single length of wire, the ends of the wire being extended to form a neck 4 which passes through an opening in the top piece 2, and also through a washer 5 fitted against the lower face of the top piece. At the lower end of the neck 4 the ends of the wire are diverged at 6 and received within a diametrically disposed crimp in a plate 7 which fits against the washer 5, the extremities of the wire being returned at 8 into engagement with notches 9 in the edges of the plate 7.

The sheave 10 is journaled upon a shaft 11 which passes through corresponding openings in the lower ends of the side plates 1, the extremities of the shaft extending beyond the side plates and receiving the cotter-pins 12 which engage ears 13 stamped from and pressed outwardly from the side plates 1. In this manner the shaft 11 is not only held against longitudinal movement, but is also locked against rotation so that the shaft bearings in the side plates 1 will never become worn by rotation of the shaft therein. The sides of the sheave 10 are provided with the annular rows of depressions 14, the depressions in the opposite sides having a staggered relation, so that a maximum strength is obtained for the material used.

The rope guides may be conveniently formed of spring wire, and each have a U-shaped formation. The arms of the rope guides 15 extend along and are spaced from the opposite side plates of the pulley frame on the exterior thereof terminating at their upper ends in inwardly extending fingers 16 having the laterally projecting wings 17 at the extremities thereof. The lower ends of the rope guides 15 carry the laterally projecting guide eyes 18, said eyes being adapted to be formed by a coil in the wire 19 and serving to receive the rope 19 which passes around the sheave 10. Key-hole slots

20 are formed in the side plates 1 of the pulley frame at points toward opposite sides thereof, and the fingers 16 of the rope guides are adapted to be inserted through the key-hole slots or removed therefrom, when the 5 rope guides are swung into proper position to bring the wings 17 of the fingers into registry with the narrow ends of the key-hole slots. These key-hole slots and wings 10 17 are arranged in such a manner that the rope guides 15 must be swung into an extreme position which would never be assumed during the normal operation of the pulley, in order to bring the wings into 15 proper position for applying the rope guides to the pulley frame, or removing them therefrom. The position into which the rope guides must be swung preparatory to removing the right hand rope guide, is indicated 20 by dotted lines on Fig. 1, and just the reverse of this position would be necessary to remove the left hand rope guide. With the arms of the U-shaped rope guides arranged along and spaced from the outsides 25 of the side plates 1, the rope guides may swing upon both sides of the sheave shaft 11 to accommodate the various positions of the rope 19 relative to the sheave, which would not be possible were the arms of the 30 rope guides arranged on the insides of the side plates 1, and further this construction allows an arrangement of the key-hole slots so that the rope guides must be swung into 35 positions not ordinarily assumed in the usual operation of the sheave, in order to detach the same, so that accidental disengagement of the rope guides from the side plates is rendered practically impossible. Owing to the fact that the rope guides are 40 formed of heavy spring wire, it will be obvious that the arms thereof can be readily sprung apart a sufficient amount to disengage the fingers 16 from the key-hole slots, and the rope guides can be readily placed 45 in position or removed therefrom, without the necessity of using any special tool.

Having thus described the invention, what I claim as new and desire to secure by Letters Patent, is:—

50 1. The herein described pulley and rope guide, including a pulley frame formed with

spaced side plates having pivot openings therein, a sheave journaled between the side plates, and a pair of U-shaped rope guides embracing the pulley frame, the lower ends 55 of the rope guides being provided with laterally projecting guide eyes adapted to receive the rope, the arms of the U-shaped rope guides being arranged along and spaced from the outsides of the side plates and terminating 60 at their upper ends in inwardly extending pivot fingers which engage the pivot openings in the side plates, so that both of the U-shaped rope guides may swing upon both sides of the sheave shaft to accommodate the various positions of the rope 65 relative to the sheave.

2. The herein described pulley and rope guide, including a pulley frame formed with spaced side plates, having correspondingly arranged key-hole slots in the upper portions thereof, a sheave journaled between the side plates at a point below the key-hole slots, and a pair of U-shaped guides embracing the pulley frame and each formed from 75 a single length of spring wire, the arms of the side U-shaped rope guides being arranged along and spaced from the outsides of the said side plates, and the lower ends of the rope guides being provided with laterally projecting guide eyes adapted to receive the rope, while the upper ends of the arms of the U-shaped guide members terminate in inwardly extending pivot fingers which have lateral wings at the extremities 80 thereof, said pivot fingers being insertible through the key-hole slots when the lateral wings are in registry with the narrow ends of the slots, and the wings and slots having such a relation to each other that the rope 85 guides must be swung into extreme positions, not ordinarily assumed in the usual operation of the pulley, for attaching to or detaching from the pulley frame.

In testimony whereof I have signed my 95 name to this specification in the presence of two subscribing witnesses.

JOHN N. ANKROM.
